ROTARY SHEAR

William A. Sabo, Neshaminy, Pa.

Application April 5, 1955, Serial No. 35,370

Term of patent 14 years

(Cl. D55—1)

FIG. 1

FIG. 2

FIG. 3

FIG. 4

Fig. 1 is a front elevational view of a rotary shear embodying my new design;

Fig. 2 is a top plan view thereof;

Fig. 3 is an end view thereof, looking toward the shear end of the rotary shear; and

Fig. 4 is another end view thereof, looking toward the handle end of the rotary shear.

I claim:

The ornamental design for a rotary shear, as shown.
